United States Patent

Des. 236,679
Patented Sept. 9, 1975

236,679

COMBINED CABINET AND ELECTRIC COUNTER TOP COOKING UNIT

Philip H. Peters, Jr., Washington County, and John L. Matrone, Albany County, N.Y., assignors to Environment/One Corporation, Schenectady, N.Y.

Original design application Sept. 23, 1971, Ser. No. 183,288. Divided and this application Nov. 21, 1973, Ser. No. 417,966

Term of patent 14 years

Int. Cl. D7—02

U.S. Cl. D7—121

FIG. 1

FIG.2

FIG.3

FIG. 4

FIG. 5

FIG. 1 is a perspective view of a combined cabinet and electric counter top cooking unit showing our new design;

FIG. 2 is a top plan view thereof;

FIG. 3 is a front elevation view thereof;

FIG. 4 is a rear elevation view thereof; and

FIG. 5 is a side elevation view thereof.

The characteristic features of the design reside in the smooth top surface appearance of the electric counter top cooking range together with associated control knobs and dials on the front edge portion and cooking site identification marks on the smooth top surface.

This is a divisional application of pending prior design patent application Ser. No. 183,288, filed Sept. 23, 1971.

We claim:

The ornamental design for a combined cabinet and electric counter top cooking unit, as shown and described.
